UNITED STATES PATENT OFFICE.

CHARLES THOMAS MASON, OF SUMTER, SOUTH CAROLINA, ASSIGNEE TO SUMTER ELECTRICAL COMPANY, A CORPORATION OF SOUTH CAROLINA.

IGNITION-DYNAMO.

1,140,386.

Specification of Letters Patent.

Patented May 25, 1915.

Application filed June 1, 1912. Serial No. 700,933.

To all whom it may concern:

Be it known that I, CHARLES THOMAS MASON, a citizen of the United States, residing at Sumter, in the county of Sumter and State of South Carolina, have invented certain new and useful Improvements in Ignition-DYNAMOS, of which the following is a specification, reference being had to the accompanying drawing.

10 My invention relates to ignition dynamos, and particularly to those of the magneto type.

The objects of my invention are; to provide a machine of increased efficiency in which the spark is of the same intensity in either the advance or retard position; to eliminate all sliding contacts and the consequent danger of loose connections; to provide a device which is readily timed with the engine without the necessity of means to indicate the position of the armature; to reduce the cost of manufacture and simplify the various parts; and to provide a method of revolving the field and armature 25 in opposite directions for producing a good igniting current at very slow speeds.

Figure 1 is a sectional longitudinal view of my magneto. Fig. 2 a sectional view on the line *a b* Fig. 1. Fig. 3 a detailed 30 view of the bearing cap, and Fig. 4 a method of driving the field and armature structures in opposite directions.

Like figures of reference denote the same parts wherever they are shown.

35 1 denotes a suitable base carrying the supports 2 and 3 for the armature shaft 4. The armature shaft is movable in these supports, which also form a bearing for a movable field structure consisting of the end 40 plates 5 and 6, carrying a suitable magnet 7. By means of the gear 8, this structure may be revolved. This movable field structure is carried in bearings in supports 2 and 3, said supports being cut away so that they 45 do not touch the armature shaft 4.

To the end plates 5 and 6 and the magnets 7 is attached the pole shoes 9 and 9^a, which revolve with the magnet structure. These may be under cut toward the magnet 50 as shown.

The armature 10 is supported by means of the non-magnetic end plates 11 and 12, and carries the winding 13, one end of which is grounded at 14, the other end con-

nected at 15 with a suitable terminal; this 55 end of the winding is insulated from the armature shaft by means of the bushing 16. A suitable wire 17 may be connected to the terminal for conducting the current to the engine igniter, the other side of the circuit 60 being completed through the frame of the igniter, engine and dynamo. Where the armature is rotated, any well known form of slip joint, many of which are well known, may be used instead of the form as shown. 65

A handle or other means 18 is provided whereby the armature may be moved so that the spark is advanced or retarded, and as this movement does not vary the relative position of the armature in relation to the 70 pole shoes and the operation of the engine igniter, the intensity of the spark remains the same with the armature in any position. Furthermore there is no limit to the amount 75 of variation between the advance and retard position, as the armature may be moved through a complete revolution. It is obvious that the armature may be fixed in any 80 desired position, by any suitable means. A magneto of this description may be belt or friction driven, but is primarily designed to be driven by gears or a chain in time with the engine igniter; and sometimes it is desirable to have the magneto moving at more 85 than engine speed, or at a greater speed than can be obtained by gears of convenient size. Now it is obvious that if the magnet field structure was moved in one direction and the armature in the reverse direction from the magnets, the speed of the moving 90 parts may be less than what it would be in case the armature was stationary and the field revolved around it. I accomplish this desirable condition by any suitable arrangement of gearing such as that shown in Fig. 95 4. The internal gear 19 is mounted on the magnet structure and meshed with the gear 20 mounted on a shaft 21, which is driven by the engine. This shaft also carries gear 22, which meshes with gear 23 connected to 100 the armature shaft 4. It will be obvious that as the shaft 21 revolves, the magnet structure driven by gear 19 will turn in one direction, while the armature structures carried by shaft 4 will revolve in the other direction and that the speed at which the magnetic flux is reversed through the winding 105 will be greater than it would be if either

part was still. By this method, I obtain a current of high igniting efficiency and yet the movement of the parts and the wear on the bearings is reduced to a minimum. The 5 parts 20, 21, and 22, are properly a part of the engine, but are here shown and described to illustrate the operation of the magneto.

The structural details of a magneto of 10 this type may be varied within wide limits without departing from the essential features of my invention. The only detail of construction that may not be clearly understood is the method of mounting the armature and magnet structures in their supports. Fig. 3 illustrates one method of accomplishing this. The support 2 is split 15 and a cap 24 forms the upper part of the bearing, this being attached to the support 20 by any suitable means such as the screws 25. Another method which I find suitable is to split the base on the line *a b* Fig. 1, and bolt the two sections together in a man-

ner that will be readily understood by any 25 mechanic.

I claim:

In an ignition dynamo, an armature, a shaft therefor, supports for said shaft, a field structure revoluble about said armature comprising a plurality of circular permanent magnets, end plates secured to said magnets and forming therewith a housing for said armature, supports for said field structure concentric with said armature 30 supports and clear from said shaft, driving means secured to said field structure whereby same may be revolved, means connected to said armature whereby its position may be manually varied, and a circuit connection through said shaft to said armature. 35

In testimony whereof I hereunto affix my signature in the presence of two witnesses.

CHARLES THOMAS MASON.
